UNITED STATES PATENT OFFICE.

JOHN ROY STARK, OF RACINE, WISCONSIN.

MAGNETO IMPULSE STARTER.

1,235,077.

Specification of Letters Patent. Patented July 31, 1917.

Application filed February 24, 1917. Serial No. 150,749.

To all whom it may concern:

Be it known that I, JOHN ROY STARK, a citizen of the United States, residing at 1516 Thurston Ave., Racine, Wisconsin, have invented certain new and useful Improvements in Magneto Impulse Starters, of which the following is a full and complete specification, reference being had therein to the accompanying drawings.

10 This invention relates to mechanism for driving a magneto ignition generator from an internal combustion motor, this mechanism being of a type which employs a resilient connection between the driving means and the magneto rotor shaft, which at low engine speeds is alternately placed under tension and then released, accelerating the speed of the magneto rotor relative to that of the driving means at each ignition period, 15 and thereby producing a strong and efficient spark at low engine speeds.

In devices of this nature heretofore used, it has been found that the resilient connection between the driving means and the 20 magneto rotor becomes troublesome at high speeds, the same introducing a variable lag into the drive on account of the variable magnetic torque of the magneto rotor, this lag being greatest just at a time when the 25 spark should occur in an early or advanced position, (at high engine speeds), and hence the efficiency of the magneto is more or less affected by such action. This difficulty may be overcome by the use of a very stiff 30 resilient means or spring, but at low speeds, the use of such a spring throws considerable 35 strain on the release mechanism and as a consequence, the same is soon worn out or broken.

40 It is the general object of this invention to provide a simple structure of the class described to produce an efficient spark at low engine speeds, and which does not interfere with the proper operation of the 45 magneto at normal or high engine speeds.

It is a further object of this invention to provide a structure which is entirely automatic in action, and in which the non-synchronous operation of the magneto at starting, automatically becomes synchronous as 50 soon as the engine attains its normal speed.

It is a still further object of the present invention to provide a simple combined supporting and inclosing means for such 55 structure.

For the purpose of rendering the in-

vention more clear, reference is had to the accompanying drawings in which Figure 1, shows a cross section elevational view of one form of the device, in structural relation with a magneto; Fig. 2, shows a section along line 2—2 of Fig. 1; Fig. 3, is a plan view; and Fig. 4, shows in detail, the structure of the dog and release arms and their relation to the driving and driven members.

The rotor shaft 1 of a magneto 2 has fastened or keyed upon its end a disk 8, shaft 1 rotating in a ball bearing 6 located in an end plate 5, which as shown is structurally integral with the magneto 2, the bearing 6 forming the front magneto bearing. It should be understood, however, that if desired the invention may be embodied in an individual structure adapted to be utilized in combination with any of the well known types of magnetos. Supported by the casing 4, is a second bearing 7, in which a shaft 3 is mounted in axial alinement with shaft 1. Secured upon shaft 3 is a second disk 9, provided with a central hub 10, having a circular recess into which fits a boss or projection 11 fixed upon disk 8, this projection serving to center and support the members 8 and 9 in proper relation to each other. Carried upon the inner face of the disk 9, and projecting perpendicularly therefrom, are two pivot pins 12 and 12^a, these pins being located at diametrically opposite points on the said disk. Located on the inner face of the disk 8, and similarly mounted, are two other pivot pins 13 and 13^a. Mounted upon and connecting the pivot pins 12 and 13, is a flat steel spring 14, a second spring 15 being similarly mounted upon the pins 12^a and 13^a. The pivot pins 95 are so located in the disks 8 and 9 and the disks so angularly positioned to each other, that the springs 14 and 15 lie parallel to each other and are both tangent to a circle whose center is located at the axis of rotation of 100 the disks.

Located at diametrically opposite points on the edge of disk 8 are two notches 16, these notches being located in the center of depressions formed in the edge of the disk. This is clearly shown in Fig. 4, in which the dotted lines show the original contour of the disk. The edge of disk 9 carries two depression cam surfaces 17 located diametrically opposite each other, as shown in 110 Fig. 2.

The release mechanism which is mounted

in a recess 18, formed in the casing above the disks 8 and 9, consists of a hub 19 with integral arms 21 and 22, arm 21 being provided at its end with a dog or projection 24, 5 and the arm 22, with a fiber block 23, this block being located to coöperate with the depression cams 17 of the disk 9, while the dog 24 coöperates with the notches 16 of disk 8. The hub 19 is fulcrumed by the 10 two projecting shafts 20 which find bearing in the two portions of the casing 4 and 5. As shown in Fig. 1, the casing members 4 and 5 completely inclose the structure and a filling plug 25 may be used to introduce 15 a suitable lubricant into the interior of the casing. The piece 18^a is a portion of the housing 4 which extends across the recess 18 and is of assistance centering the housing 4 on the bearing plate 5.

20 The operation of the device is as follows:—Assuming the shaft 3, which is positively geared to the engine crank shaft, to be rotated in an anti-clock-wise direction, the disk 9 will rotate the disk 8 by means of 25 the connection existing between the two disks in the form of the springs 14 and 15. The disk 8 will continue to rotate until the dog 24 drops by gravity into the notch 16, this action being rendered possible, owing 30 to the fact that the fiber block 23 has already entered one of the depression cam surfaces 17 of the disk 9, thereby allowing the dog 24 to drop far enough to coöperate with the notch. As the driving member or disk 9 35 continues to rotate, and the driven member or disk 8 is held stationary by the dog 24, the springs 14 and 15 are deformed into the curved positions shown in dotted lines in Fig. 2, thereby storing potential energy. As 40 the disk 9 rotates still further, the cam surface 17 passing under the fiber block 23, gradually returns to normal, lifting fiber block 23, and through arms 21 and 22, lifting the dog 24 out of the notch 16, thereby 45 releasing the disk 8 and allowing the same to suddenly rotate under the action of the energy obtained from the springs 14 and 15 as they assume their normal parallel positions. The magneto rotor is thereby given two 50 quick impulses per revolution of the shaft 3, the notches 16, 16, and the cam surfaces 17, 17, being angularly located with reference to the magneto rotor, to give the impulses at the proper spark producing positions of the rotor.

55 After the engine has started and its speed becomes normal, the peripheral speed of the disks 8 and 9 becomes too great to allow the dog 24 time to drop far enough into the depressions in the edge of disk 8 to enter the notches 16 and the dog and release mechanism thereby automatically become inoperative. The magneto rotor is now driven at 60 synchronous speed, the necessary torque being transmitted from the driving member 9

to the driven member 8 by means of the flat springs 14 and 15. As these springs are tangent to a circle with the axis of rotation as its center, the greater part of the power is transmitted through the springs in the 70 form of a thrust along their axes, and the springs therefor offer considerable resistance to any initial deformation. After initial deformation has occurred, however, the remaining deformation of the springs 14 and 75 15 requires much less effort, and the flat springs therefor form resilient connecting means possessing a variable deformation resistance. It is therefore possible in a structure of the type just set forth, to design the 80 flat springs so that they will transmit the necessary torque to drive the magneto rotor without deformation, and yet when the springs function at starting, they will not throw a heavy and excessive strain on the 85 release mechanism.

As shown in the drawings, the springs 14 and 15 should be provided with some means for preventing an inward or reverse deformation, this being prevented in the structure 90 shown by placing the springs tangent to the hub 10.

What I claim is:—

1. In a magneto impulse starter, the combination with a driving member, of a driven 95 member, and means comprising a flat spring for connecting said driving member and said driven member together, said spring being pivotally connected to both of said members.

2. In a magneto impulse starter, the combination of a driving shaft and a driving disk mounted thereon, with a driven shaft and a driven disk mounted thereon, said driven shaft being in alinement with said driving shaft; and means for connecting said 100 driving disk and driven disk together comprising a plurality of flat springs, the axes of which are tangential to a circle whose center is in the axis of rotation of the driving shaft.

3. In a magneto impulse starter, the combination with a magneto rotor shaft, of a driven disk fixed thereto, a driving disk coaxially related to said driven disk, flat resilient means connecting said driving and 105 driven disks together, a notch in the edge of said driven disk, a dog arranged to coöperate with said notch to prevent rotation of said driven disk, and means carried by said driving disk to disengage said dog from said 110 notch.

4. In a magneto impulse starter, the combination with a magneto rotor shaft, of a driven disk fixed thereto, a driving disk coaxially related to said driven disk, yielding 115 means possessing variable deformation resistance connecting said driving and driven disks together, a notch in the edge of said driven disk, a dog arranged to coöperate with said notch to prevent rotation of said 120

driven disk, and means carried by said driving disk to disengage said dog from said notch.

5. In a magneto impulse starter, the combination with a magneto rotor shaft, of a driven disk fixed thereto, a driving disk coaxially related to said driven disk, resilient means connecting said driving and driven disks together, a depression in the edge of said driven disk; a notch located in said depression, a dog arranged to enter said notch under the influence of gravity to prevent rotation of said driven disk, and means carried by said driving disk to disengage said dog from said notch, said depression being of such contour as to prevent the dog from entering the notch when the peripheral speed of the driven disk attains a certain value.

20. 6. In a magneto impulse starter, the combination with a magneto rotor shaft, of a driven disk fixed thereto, a driving disk coaxially related to said driven disk, resilient means comprising a plurality of flat springs for connecting said driving and driven disks together, a depression in the edge of said driven disk, a notch located in said depression, a dog arranged to enter said notch to prevent rotation of said driven disk, and means carried by said driving disk to disengage said dog from said notch, said depression being of such contour as to prevent the dog from entering the notch when the peripheral speed of the driven disk attains a certain value.

35. 7. In a magneto impulse starter, the combination with a magneto rotor shaft, of a driven disk fixed thereto, a driving disk coaxially related to said driven disk, resilient means for connecting said driving and

driven disks together, a depression in the edge of said driven disk, a notch located in said depression, a dog arranged to enter said notch to prevent rotation of said driven disk, and means carried by said driving disk to disengage said dog from said notch, said depression being of such contour as to prevent the dog from entering the notch when the peripheral speed attains a certain value.

45. 8. In a device of the class described, the combination of two casing members coöperating with each other to form a closed casing, a shaft rotatably supported by each of said casing members; magneto impulse starter mechanism connected to said shafts, and located within said casing, and comprising driving and driven members, resilient means connecting said members together, and stop and release mechanism for controlling the operation of said members, said stop and release mechanism being located in a recess formed at the top of said casing.

50. 9. In a device of the class described, the combination of two casing members coöperating to form a closed casing, a shaft rotatably supported by each of said casing members, said shafts being in axial alignment; magneto impulse starter mechanism connected to said shafts and located within said casing, and comprising driving and driven members, resilient means for connecting said members together, and stop and release mechanism for controlling the operation of said members, said stop and release mechanism being located in a recess 55 formed at the top of said casing.

60. In testimony whereof I have hereunto set my hand.

JOHN ROY STARK.
